UNITED STATES PATENT OFFICE.

OSCAR W. HERD, OF TULARE, CALIFORNIA.

INCUBATOR AND BROODER.

1,386,569.

Specification of Letters Patent. Patented Aug. 2, 1921.

Application filed May 27, 1920. Serial No. 384,777.

To all whom it may concern:

Be it known that I, OSCAR W. HERD, a citizen of the United States, residing at Tulare in the county of Tulare and State of California, have invented new and useful Improvements in Incubators and Brooders, of which the following is a specification.

This invention relates to incubators, brooders and the like, and has for its object the provision of improved electric heating means for a device of this character.

The invention will be readily understood from the following description of the accompanying drawings, in which—

15 Figure 1 is a perspective view of a brooder constructed in accordance with the invention.

Fig. 2 is a longitudinal section through the brooder.

20 Fig. 3 is a plan view of the brooder from the under side.

Fig. 4 is a diagrammatic showing of the wiring for the electric heating system.

The invention is illustrated as embodied 25 in a brooder having side walls 1, end walls 2 and a top 3. The end walls, preferably, comprise double spaced walls having an opening 4 leading from the exterior of the brooder to the space between the double end 30 walls, and openings 5, preferably, extend from the spaces between the double end walls to the interior of the brooder. A pipe 6 may extend outwardly through the top of the brooder for completing the ventilation provided through the brooder by the 35 opening 4, the spaces between the double end walls, and the openings 5.

A removable thermometer 7 may be projected into the interior of the brooder 40 through a suitable opening 8 in the top thereof. A thermostat 9 of any well known or preferred construction may be mounted upon a bracket 10 within the brooder, the operating rod 11 of this thermostat, preferably, extending through the top of the brooder and engaging a spring strip 12 which is normally in contact with a contact pin 13. The actuating connection between rod 11 and strip 12 may be adjusted in any 45 well known or preferred manner. A terminal 14 is provided upon the contact strip 12 and a terminal 15 is similarly arranged upon the contact pin 13. A pilot lamp 17, which is a usual incandescent electric lamp, 50 is mounted within the brooder in a usual socket 18. A socket 19 is, preferably,

mounted upon the top of the brooder, this socket being arranged to detachably receive any usual plug 20 having the cord 21 leading to a source of electrical energy. 60

The electric heating means provided in the brooder may comprise a series of electrically insulated hooks 21' arranged along opposite side walls of the brooder. An electric wire 22 is strung back and forth from a hook at one side of the brooder to a hook at the opposite side thereof, and the terminals of this wire are, preferably, connected to the terminals of the lamp socket 18. The wire 22 is a wire adapted to afford sufficient resistance to the current supplied to the brooder as to cause heating of the wire for maintaining the desired temperature in the brooder. 70

One of the terminals of the lamp socket 75 18 is, preferably, connected to the terminal 15 of contact pin 13, and the other terminal of the lamp socket is, preferably, connected to one terminal of socket 19, the other terminal of which is connected to the terminal 14 of the contact strip. Thus it will be seen that when contact strip 12 is in normal position in contact with contact pin 13, a circuit will be closed therethrough and through the pilot lamp and the heating wire 22. As 80 soon as the thermostat 9 is actuated, when the desired temperature is reached in the brooder, the contact between strip 12 and pin 13 is broken and the circuit through the pilot lamp and the heating wire 22 will 85 be consequently broken. 90

It will be observed that the construction thus described provides an extremely simple heating means for a brooder and the like, said heating means and the controlling apparatus therefor being conveniently positioned upon the brooder. 95

Various changes may be made without departing from the spirit of the invention as claimed. 100

What is claimed is:

A device of the character described comprising a chamber to be heated, a plurality of insulated hooks extending along opposite walls of said chamber, an electric heating wire strung upon said hooks, a thermostat mounted upon said chamber, and an electric circuit through said thermostat and through said heating wire. 105

In testimony whereof I have signed my 110 name to this specification.

OSCAR W. HERD.
